UNITED STATES PATENT OFFICE.

HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

TELEPHONE SIGNALING SYSTEM.

Application filed October 16, 1924. Serial No. 743,883.

This invention relates to telephone systems, and more particularly, to signal receiving equipments associated with toll line systems.

In the present practice in regard to toll line traffic, means are usually provided for disconnecting the incoming end of toll lines from one terminating signal receiving equipment and connecting it to another terminating equipment. The reason for performing such transfers may arise from a variety of causes, such as for example, the failure of a particular terminal equipment to function properly, or the desire to regulate or equalize the traffic load between positions at a toll office. Whatever the causes may be, it is not unlikely that the terminating equipment to which a toll line is to be transferred is not equipped to function with that particular type of toll line. In these cases, suitable intermediate equipment such as composite ringer sets or other signal translating devices have to be provided and inserted between the toll line and the terminal equipment.

It is an object of this invention to overcome the above difficulties in regulating toll traffic by the provision of a terminal equipment that will function with any type of toll line now in use and that may be attached to any toll line by merely transferring the conductors of the toll line from any ordinary terminating equipment to the conductors of a terminating equipment arranged in accordance with this invention.

Another object is the provision of a terminating equipment of the above type that will respond to signaling current incoming over a toll line regardless of the character of such signals, that is, the signals may be in the nature of alternating or direct current; combinations of various frequencies or in fact any current that when received in the primary of the usual transformer will induce alternating current in the secondary, as for example, a voice modulated current.

Another object of the invention is the provision of terminating equipments in which a part of the devices or apparatus used may be common to a plurality of individual terminating equipments.

To attain these objects in accordance with one feature of the invention, a rectifying device of the two-plate single filament vacuum

tube type is provided to produce a unidirectional continuous current in the winding of a relay, which in turn, is adapted when operating to cause the actuation of a signal.

Another feature is the provision of circuits whereby the above mentioned vacuum tube is made common to a plurality of terminating equipments so that any number of such equipments may function to operate their respective signals simultaneously without interference.

Another feature of this invention is the provision of a circuit arrangement including a transformer and the common vacuum tube for the reception of any kind of signaling current. The primary of this transformer is connected to the incoming end of a toll line and the secondary is connected respectively at its outer terminals to the input terminals of the double-plate vacuum tube, while the central point of this winding is connected through the winding of a pulsating direct current responsive relay to the filament of the tube in such a manner that any current changes in the primary winding may by inducing an alternating current in the secondary winding cause a direct fluctuating current to pass through the relay and operate the same.

These and other features of the invention will become apparent in the following description which will be made in connection with the accompanying drawing in which the terminating circuit equipments of two toll lines are shown and arranged with a common vacuum tube.

Referring now to the drawing the incoming end of the toll line 1 is shown connected to the primary of a transformer 2 of a terminating equipment 50. The secondary of this transformer is arranged to terminate in jacks 4, 5, and 6, at an inward, a through, and an outward position respectively. A signal lamp 7 and busy signal 8 are associated with the inward jack 4 and a lamp 9 and busy signal 10 are associated with jacks 5 and 6. A key 11 for transferring the signal operating means from the inward position to the through and outward positions is also shown and arranged as is well-known in the art. A common vacuum tube 20 of the rectifying type having two plates and a single filament is shown connected to the

secondary of the transformer 2 and a relay 21 so that unidirectional current is produced in the relay 21 in response to current changes in the toll line 1. The leads from the vacuum tube 20 are connected similarly to relay 21' and transformer 2' at the terminating equipment 60 associated with a toll line 100. These vacuum tube leads may also be connected in a similar manner to other terminating equipments at the same or other positions in a toll line office. Similar reference characters have been used for terminating equipments 50 and 60 to designate corresponding parts.

The arrangement for transferring or eliminating the terminating equipments 50 and 60 and others from their corresponding toll lines has not been shown as it forms no part of this invention and is well known in the art. It generally consists merely of patching jacks inserted in the toll line conductors and patching cords by means of which a terminating equipment may be cut off from its toll line, and transferred to another toll line or in case it is disabled another terminating equipment may be substituted therefor.

The operation of the signals 7 or 3 in response to a signaling current received at the incoming end of a toll line 1 will now be described. It will be noted that any changes in the character of a current incoming over the conductors of the toll line 1, will when passing through the primary of transformer 2 induce an alternating current in the secondary windings of the transformer. Assuming then that when the change takes place in one direction, a current will be induced in the direction of the solid arrow shown at the upper part of the secondary winding. This current will then pass through this portion of the winding through the upper armature and back contact of relay 25, through the vacuum tube 20, from plate 26 to filament 27 thence through the winding of relay 21, back to the upper portion of the transformer, on the other hand no current will pass through the lower portion of the secondary as the vacuum tube 20 will pass currents of but a single polarity as is well-known in the art. A change in the primary of the incoming current in the opposite direction will induce a current in the lower portion of the secondary in the direction indicated by the dotted arrow, causing this current to flow from the lower portion of the secondary to the outer lower armature of relay 25, through the vacuum tube 20, from plate 28 to filament 27 thence through the winding of relay 21 back to the lower portion of the secondary winding. It will thus be noted that for every change that takes place in the primary of transformer 2, a corresponding current is produced through the winding of relay 21 in the same direc-

tion. Relay 21 is so designed as to respond to any unidirectional current impulses through its winding and maintain its armature attracted even though such impulses may be a comparatively unstable character.

When relay 21 operates it closes a circuit for relay 30 as follows: battery, lower winding of relay 30, armature and front contact of relay 21 to ground. Relay 30 operates and closes a circuit for the busy signals 8 and 10 as follows: battery, lower armature and front contact of relay 30, windings of signals 8 and 10 to ground. The operation of relay 30 also closes a circuit for signal 7 as follows: battery, make-before-break contacts of relay 25, upper armature and front contact of relay 30, upper armature and back contact of relay 31, through the lamp 7 to ground, causing this lamp to become illuminated to notify the inward operator that her attention is required at jack 4 of this particular trunk. Relay 30, in operating its upper armature and front contact closes an obvious locking circuit for itself through its upper winding from the battery at the make-before-break contacts of relay 25.

When now the inward toll operator responds to this signal by inserting a plug in jack 4 as is well-known in the art, a circuit is completed for relay 25 as follows: battery, at the inward operator's cord circuit (not shown) through the sleeve contacts of the associated plug and the jack 4 through the lower armature and back contact of relay 31, winding of relay 25 to ground. This causes the energization of relay 25 which now opens at its make-before-break contacts the locking circuit for relay 30. The circuit for lamp 7 is also broken at the make-before-break contact of the relay 25 as is obvious causing the lamp to become extinguished. However, the circuit for busy signals 8 and 10 is maintained operated, after the release of relay 30, from battery, supplied at the inner lower armature and front contact of relay 25.

In case the inward operator desires to transfer the incoming call to the through operator or the outward operator, she operates her transfer key 11 which closes an obvious circuit for relay 30 and 31, causing these two relays to operate. As she removes her plug from jack 4, relay 25 releases, causing the circuit to be completed for lamp 3 as follows: battery, make-before-break contact of relay 25, upper armature and front contact of relay 30, upper armature and front contact of relay 31, through lamp 3 to ground. As is well known in the art either one of the operators at the through or outward position may answer this call by inserting a plug in jack 5 or 6 as the case may be. Relay 25 will then be operated in the same manner as when the inward operator inserted her plug

in jack 4 and the operation of relay 25 in this instance causes the same actions to take place as previously mentioned to maintain busy signals 8 and 10 operated and to extinguish lamp 3 and release relays 31 and 30. It should be noted that when relay 25 operated in response to an insertion of a plug in jack 4, 5, or 6, the circuit from the secondary of transformer 2, through the 10 vacuum tube 20 is broken at the upper armature and back contact and the outer lower armature and back contact of this relay, so that even though a signaling current may be present on the toll line, no current will flow through the winding of relay 21 and this relay will, consequently, release and have no further effect on relay 30, which, as stated, is now free to release by the 15 opening of the locking circuit through its upper winding to the battery at the make-before-break contacts of relay 25.

As the terminating equipment 60 is identical with the terminating equipment 50, no further description is made in regard to 20 this equipment except to say that the leads 62, 63 and 64 from vacuum tube 20 are connected through the relays 25' and 21' and transformer 2' of this equipment in exactly the same manner as they are connected to 25 the corresponding parts of the terminating equipment 50. It should also be understood that these leads may be extended to as many other similar terminating equipments in the toll office as may be desired, it being immaterial as far as the action of the vacuum tube 20 is concerned how many terminating equipments are connected, and it is evident that signals may be received through 30 any number of trunk lines simultaneously and cause the vacuum tube 20 to function without any danger of having the signals interfere with each other, as this vacuum tube merely serves as a means for the passage of current through the individual relays 21, 21' etc. of the various terminating equipments.

What is claimed is:

1. In a signaling system, a vacuum tube rectifier and a plurality of signal responsive equipments, each of which includes a relay and a transformer connected to said rectifier so that signaling current incoming to an individual signal responsive equipment will affect the operation of said relay

and a signaling means actuated by the operation of said relay. 55

2. In a signaling system, a vacuum tube rectifier and a plurality of signal responsive equipments, each of which includes a relay and a transformer connected to said 60 rectifier so that signaling current incoming to an individual signal responsive equipment will produce a uni-directional operating current for said relay and a signaling means actuated by the operation of said relay. 65

3. In a signaling system, a vacuum tube rectifier having two plates and a single filament cathode, a plurality of signal responsive equipments, each of which includes a relay and a transformer connected to said 70 rectifier with the outer ends of the secondary of the transformer connected to the plates and with a central point of the secondary of the transformer connected through the winding of the relay to the filament 75 cathode for the production of a unidirectional operating current for said relay when an alternating current is induced in the secondary due to a current change in the primary of said transformer and a signaling means actuated by the operation of 80 said relay.

4. In a signaling system, a plurality of toll lines, signals associated with the terminating ends thereof, means for operating 85 said signals in response to incoming currents over said toll lines comprising a rectifying device common to said toll lines, and incoming current responsive means individual to each toll line arranged to cooperate 90 with the common rectifying device to cause the operation of the corresponding signals.

5. In a signaling system, a plurality of toll lines terminating in signals, means for controlling said signals comprising a vacuum tube rectifier common to said toll lines, a relay and a transformer individual to each toll line so arranged and connected with the common rectifier that current of any character incoming over a toll line will produce a unidirectional operating current for the operation of the corresponding relay and means controlled by said relay to actuate the corresponding signals. 95 100

In witness whereof, I hereunto subscribe 105 my name this 10th day of October A. D., 1924.

HENRY W. O'NEILL.
